UNITED STATES PATENT OFFICE.

JOSEPH A. HAIGH, OF SUNBURY, PENNSYLVANIA.

CARBURETER.

1,242,180.

Specification of Letters Patent. Patented Oct. 9, 1917.

Application filed August 17, 1914, Serial No. 857,149. Renewed February 27, 1917. Serial No. 151,379.

To all whom it may concern:

Be it known that I, JOSEPH A. HAIGH, residing at Sunbury, in the county of Northumberland and State of Pennsylvania, have 5 invented a new and Improved Carbureter, of which the following is a specification.

This invention has reference to carbureting means for explosive engines and it primarily has for its object to provide an improved 10 means of the character stated of a simple and economical construction and in which the co-operative parts are designed for automatically regulating the fuel and air in such a manner as to produce a proper mixture of the working agent for giving 15 maximum power to the engine when desired, and to vary the fuel and air infeeds to suit the corresponding requirements.

Another and important object of my invention 20 is the provision of an improved construction of carbureter in which the parts are so arranged and operatively connected whereby the high speeds of the motor tend to automatically adjust the set of the carbureter to control the feed of the gasolene 25 and to regulate the same in the proper or desired proportions to the amount of the air that is drawn from the air infeed past the gas discharging nozzle to the mixing chamber.

With other objects in view that will be hereinafter explained my invention is an improved carbureter that embodies the peculiar features of construction and novel 35 arrangements of parts, hereinafter described, specifically pointed out in the appended claims, and illustrated in the accompanying drawings, in which:

Figure 1 is a vertical section of my improved 40 carbureting mechanism for explosive engines, the gasolene supply tank being shown in side elevation and the sliding vanes or air controlling means being shown closed,—the position they assume when the engine is running under a low speed.

Fig. 2 is a similar and enlarged view of the carbureter devices proper, the parts being positioned as indicated in Fig. 1, the sliding tube and the gas nozzle being shown 50 in section.

Fig. 3 is a view similar to Fig. 2, on the line 3—3 of Fig. 2 the operative parts being shown in the position they assume when the engine is running on a high speed.

Fig. 4 is a horizontal section taken practically on the line 4—4 on Fig. 2.

Fig. 5 is a similar view taken on the line 5—5 on Fig. 3.

In carrying out my invention the carbureter casing 1, is formed integral with the fuel reservoir tank 2, of any suitable construction, and provided with the usual float 3 and controlling valve 4, as indicated on Fig. 1.

5 designates the air inlet that opens into the bottom of the casing 1 and 6 is the mixing chamber in the upper end of the casing 1, and the said upper end has the usual flange 7 for connecting with the engine casing.

9 designates a tubular arm that extends radially from one side of the casing or cylinder 1, and it is held in communication with the supply port 11 from the gasolene reservoir, the feed passage of which is controlled by an adjusting valve 12, as shown.

Arm 9 terminates in a vertically extending tubular member whose upper end is tapered and forms the nozzle 90 from which the gaseous fuel discharges into the mixing chamber 6.

A tube 13 is slidably mounted on the nozzle 90 and the lower portion of the said tube is reduced and shaped to form pendent saddle arms or hangers 14, the lower ends of which are integral with or otherwise fixedly joined with the base or saddle piece 15, which forms a seat for a coiled tension spring 16, the upper end of which bears against a top plate or button 17 on the stem 18 of an adjusting screw 19 that passes through the saddle piece 15 and through an aperture 10 in the bottom of the casing 1, and whose lower end terminates in a turning head 20.

Tube 13 has a series of elongated slots or air passages 13^a adjacent the upper end thereof, and at the lower ends of the said slots the said tube has radially projected bifurcated apertured ears 21, with each of which pivotally connects a link member 22, presently referred to.

28 designates a ring flange or collar fixedly mounted on the upper end of the nozzle that forms a division member between the tube 13 and the nozzle, and the said ring has air passages 28^a, as shown.

8 designates a partition or division member, mounted within the casing in the space between the nozzle tube and the side of the casing and the said partition includes an annular top slide member 82 and an annular

lower or bottom slide 83, the latter being of substantially triangular shape in cross section, whereby to form an inclined surface that opposes an inclined surface 81 on the 5 upper partition member 82, the said two surfaces forming, as it were, an annular inclined slideway or groove 88, the purpose of which will presently appear.

Cooperatively mounted on the partition 10 and forming the air controlling elements are a series of vanes, each being in the nature of a double frusto conical segment 23, the upper section 24 being smaller than the lower section 25, and the said upper sections 15 are projected at such an angle that they freely engage and move within the annular slideway or groove formed in the partition, and as is clearly shown in the drawing.

The several segments or vanes, when at 20 one position, are held closed against each other to form, as it were, a Venturi tube or passage around the nozzle, and the restricted apex end of the said tube is of such diameter that when the segments are closed 25 against each other, as shown in Fig. 1, the upper end of the tube 13 closes the said end of the Venturi tube, when the engine is running at the low speed, as in Fig. 1, by reference to which it will be noticed that 30 each of the segments is connected to one of the links 22 that join with the tube 13 and by reason thereof, as the tension of the spring pulls the tube 13 down to its lowermost position, that is, with the solid upper 35 end over the apertured collar on the nozzle, the segments or vanes are pulled downwardly and inwardly to close against each other and against the upper end of the tube 13, thereby closing the air passage between 40 the tube and the casing and forming an indirect or restricted air passage through the tube and the air passages 28 in the collar 28 on the nozzle.

At this point, it should be stated, that 45 when the parts are adjusted as shown in Fig. 1, the tension of the spring 16, is such that it holds the segments or vanes closed to feed the air directly over the nozzle for intermixing with the gasoline as it is ejected 50 into the mixing chamber, it being understood that when the air suction or pressure exceeds the tension or back pull of the spring 16, the segments or vanes spread apart, and form direct air passages from 55 the air infeed to the mixing chamber.

By reason of the peculiar construction and novel arrangement of the several parts that constitute my improved carbureter, I have provided a simple and effective means 60 for automatically effecting the proper mixture of the working agent to suit the requirements at different speeds and powers of the engine.

By forming the air controlling element 65 of a series of vanes shaped to form a closed

Venturi tube when drawn together and to approximately maintain such shape when opened or spread, the said element, as it is expanded or opened out, even to its fullest extent (and in the manner presently stated) 70 serves as a Venturi tube whose area varies in accordance to the position of the sections or vanes that constitute the said tube, it being understood from the drawings, that the said vanes open or spread under atmospheric pressure or suction, automatically in proportion to the engine speed and load. 75

To further provide for a perfect adjustment or flow of the gasoline to suit the engine requirements, a taper pin or needle 80 valve 30 is attached to a bracket piece 31 secured upon the upper end of the slotted tube 13, and the said pin or valve 30 moves within the gasoline nozzle to open and close the gasoline nozzle, partly and proportionately, as it acts in conjunction with the sliding vanes, before referred to, for automatically controlling the outfeed of the gasoline through the said nozzle. 85

In operation, when the engine is running 90 at low speed, the several vanes are at the closed position (see Figs. 1 and 2) and when thus set, the tube 13 that slides over the fuel nozzle is at its lowest position, and at this adjustment the upper ends of the air 95 slots therein are closed by the apertured collar 28 on the nozzle, which now causes the air to flow from the air chamber through the slots in the tube 13, and the air openings in the collar, it being understood since 100 the vanes now form a closed Venturi tube of a small area, a small air supply is led into the mixing chamber, and a consequent low air pressure and suction exists that produces a proportionately small supply of the 105 fuel to the mixing or carbureting chamber, it being understood that the vanes together with the sliding tube are held down under spring tension. 110

As the engine speeds up, and the suction 110 and air pressure on the vanes 24 proportionately increases, the said vanes are correspondingly separated, and as the tension or hold-back spring connected to the tube 13 (and through it with the vanes 25) now 115 puts more pressure or velocity on the air traveling through the now spread Venturi tube, it draws more gasoline from the nozzle and thus maintains an even mixture of the air and gas. 120

Among other advantages incident in the use of my improved carbureter, is that owing to the action of the air, as it strikes the vanes, the air current is caused to pass over the nozzle discharge diagonally and thereby becomes the more thoroughly mixed with gas. 125

Furthermore, as the vanes of the air controlling means separate, under the upspeeding of the engine, the air that passes up 130.

through the spaces between the vanes is under a lower pressure than the air that travels toward the center around and over the nozzle and as a result thereof, the central or high pressure air currents that are directed crosswise of the nozzle, as before stated, are caused to spread out with the other air currents into the low pressure area where it thoroughly intermixes with the gaseous fluid, and at the same time the in-feed of such fluid is cut down proportionately to the requirements of the engine.

What I claim is:

1. In a carbureter, a gasoline nozzle, a casing in which the nozzle is mounted, a tube slidable on the nozzle and having air passages adjacent to one end, a device for moving the tube downwardly on the nozzle, said nozzle and tube being spaced from the said casing to leave a passage, said casing having an air intake below and a mixture outlet above the said nozzle, a sliding partition in the casing for regulating the areas of the aforesaid passage and connections between the said partition and the said tube, whereby when the said tube is lowered the said passage around the tube will be closed, said partition being adapted to be opened by the suction of the engine, and means on the upper end of the nozzle for restricting the air passage between the nozzle and the said slidable tube.

2. In a carbureter, a casing having a mixing chamber and an air inlet, a fuel nozzle vertically mounted in the said casing to discharge into the mixing chamber, a partition in the passage between the feed nozzle and the casing, said partition including radially projected vanes adapted when in one position to close against each other to thereby form a restricted air passage around the nozzle, and to the mixing chamber, means tending to normally hold the vanes closed against each other, so long as the air pressure against them is below a predetermined amount, said vanes being mounted to spread apart as the air pressure exceeds the said predetermined amount.

3. In a carbureter, a casing having a mixing chamber and an air inlet below the said chamber, a fuel nozzle vertically projected within the casing to discharge into the mixing chamber, a tube slidable on the nozzle having air inlets adjacent its upper end, an apertured collar on the nozzle that forms a division between the tube and nozzle, means tending to normally slide the tube downwardly to bring its air inlets below the said apertured collar, a partition that separates the mixing chamber from the air inlet end of the casing, said partition including frusto conical shaped segments, a slideway for the segments, said segments forming when in one position, a conical air duct that surrounds the slidable tube and

whose upper end closes against the upper end of the said slidable tube to thereby direct the air through the air passages in the tube and through the apertured collar on the nozzle, said segments being connected to the slidable tube to move up and down with it and to spread as the suction or air pressure against the segments overcome the means that tend to pull the said segments together.

4. In a carbureter, a casing having a mixing chamber and an air intake chamber, a nozzle for the gasoline mounted within the casing that discharges into the mixing chamber, a partition within the space between the air infeed and the mixing chamber and that surrounds the nozzle, said partition including a fixed portion having an annular slideway, a movable portion consisting of a series of segmental sections of double frusto conical shape, one portion of which is movably held in the said annular slideway, the other portion of which surrounds the nozzle, means tending to normally retract or draw the sections together to form a cone shaped air tube around the nozzle, and said segments adapted for being automatically drawn out and separated as the engine suction exceeds the retracting or back tension on the segments.

5. In a carbureter, a casing having an air inlet at the lower end and a mixing chamber at the upper end, a gasoline nozzle that extends upwardly within the casing to discharge into the mixing chamber, a partition within the passage between the nozzle and the casing, means mounted on the said partition for controlling the infeed of the air to the mixing chamber, said means including shiftable members adapted, when in one position, to close and restrict the said air passage, retracting means for normally holding the members to their closed position, said members being adapted for automatically spreading to provide freer passages for the air to the mixing chamber when the suction action of the engine is greater than the hold back tension of the retractive means that cooperate with the said members and proportionately to the engine requirements.

6. In a carbureter, a casing, a gasoline nozzle within the casing, said casing having an air intake below the nozzle and a mixing chamber above the said nozzle, a tube slidably mounted on the nozzle having vertically elongated air slots adjacent the upper end thereof, an apertured collar fixed on the nozzle that forms a partition between the nozzle and the tube, means tending to normally hold the tube down with its air slots positioned below the apertured collar on the nozzle, an annular partition that surrounds the upper end of the nozzle and the tube, said partition having an annular

slideway, an air controlling valve mechanism that consists of a series of double frusto conical segments whose upper sections slidably engage the slideway in the partition, 5 pivoted links that connect each of the said segments in the sliding tube whereby movement of the tube is transmitted to the segments to open or close them relatively to the movement of the tube, said segments being adapted for automatically spreading 10 when the engine suction exceeds an amount sufficient to overcome the tension of the means that normally pull back the sections to their closed position.

15 7. In a carbureter, a casing having an air intake chamber and a mixing chamber, a fuel feed nozzle that discharges into the mixing chamber, a partition on the casing in the space between the nozzle and the 20 casing, means for controlling the air passage from the air inlet to the mixing chamber, said means including a valve mechanism composed of segment vanes slidably mounted on the partition, a tube slidably mounted 25 on the nozzle having air passages in communication with the mixing chamber, the aforesaid vanes being adapted when in one position to close the air passage around the sliding tube and adapted to cause the air to pass 30 through the said tube to the mixing chamber, means tending to normally pull the said tube to its lowermost position, connections that join the said vanes and the said tube to close the vanes and tube to move together, 35 the said vanes and tube being adapted for being moved to open up a direct air passage from the air intake end to the mixing end of the casing when the engine suction exceeds the tension of the means for pulling the tube 40 with the vanes downwardly.

8. In a carbureter, a casing having an air inlet at the lower end and a mixing chamber at the upper end, a gasolene nozzle that extends upwardly within the casing to 45 discharge into the mixing chamber, a partition within the passage between the nozzle and the casing, means mounted on the said partition for controlling the infeed of the air to the mixing chamber, said means including shiftable members adapted, when in 50

one position, to close and restrict the said air passage, retracting means for normally holding the members to their closed position, said members being adapted for automatically spreading to provide freer passages 55 for the air to the mixing chamber when the suction action of the engine is greater than the hold back tension of the retractive means that coöperate with the said members, and proportionately to the engine requirements, and a supplemental means for controlling the ejecting passage of the nozzle, said means being connected with the shiftable members, and including a tube 60 slidable over the ejecting end of the nozzle 65 and having elongated air inlets in the upper end, and means on the nozzle for restricting the air passage between the tube and the nozzle and arranged for engaging that end of the tube having air inlets. 70

9. In a carbureter, a casing having an air inlet at the lower end and a mixing chamber at the upper end, a gasolene nozzle that extends upwardly within the casing to discharge into the mixing chamber, a partition 75 within the passage between the nozzle and the casing, means mounted on the said partition for controlling the infeed of the air to the mixing chamber, said means including shiftable members adapted, when in one 80 position to close and restrict the said air passage, retracting means for normally holding the members to their closed position, said members being adapted for automatically spreading to provide freer passages 85 for the air to the mixing chamber when the suction action of the engine is greater than the hold back tension of the retractive means that coöperate with the said members and proportionately to the engine requirements, and a supplemental means for controlling the ejecting passage of the nozzle, said means being connected with the shiftable members, the said means including a taper or needle valve vertically movable 90 within the passage. 95
